UNITED STATES PATENT OFFICE.

GEORGE THOMSON, OF CHICAGO, ILLINOIS.

HOT-AIR FURNACE.

SPECIFICATION forming part of Letters Patent No. 657,016, dated August 28, 1900.

Application filed September 25, 1899. Serial No. 731,615. (No model.)

To all whom it may concern:

Be it known that I, GEORGE THOMSON, a citizen of the United States, residing at Chicago, in the county of Cook and State of Illinois, have invented a new and useful Improvement in Hot-Air Furnaces, of which the following is a specification.

My invention relates to an improvement in the class of furnaces for heating air in which the regenerative principle is employed of passing the air to be heated and the products of combustion for heating it in relatively-contrary directions for the purpose of primarily subjecting the cool air to the products of combustion in their spent or least-hot condition and progressively to the increasing gradations of heat in the products of combustion in the course thereof to their discharge-outlet, thereby the more thoroughly to exhaust them of their heat-units and accordingly transfer the same to the air.

My object is to provide a novel construction of furnace of the class referred to whereby this principle shall be employed to the best economical advantage.

Referring to the accompanying drawings, Figure 1 is a vertical sectional view of a hot-air furnace containing my improvements, the section being taken at the line 1 on Fig. 2 and 30 regarded as indicated by the arrow. Figs. 2 3, 4, and 5 are transverse sections of the same, taken, respectively, at the lines 2, 3, 4, and 5 on Fig. 1 and viewed in the direction of the arrows, but showing the burner in Fig. 5 in 35 plan elevation. Fig. 6 is a developed diagrammatic sectional view taken at the line 6 6 on Fig. 4 and regarded as indicated by the arrows; and Fig. 7, a broken section taken at the line 7 on Fig. 2 and viewed in the direction of the arrow.

A is the outer sheet-metal shell or casing, shown rising from a suitable base B and with a covered cone frustum-shaped or upwardly-tapering dome C, provided with the circumferential series of flanged openings a a, from which to extend the hot-air-conducting pipes (not shown) to the different apartments to be heated. Another sheet-metal casing D within and concentric with the outer shell forms 45 therewith an air-heating chamber E and with a similar inner shell F the circulating-chamber G for the hot products of combustion, hav-

ing at its base a discharge-duct p, leading through the outer shell. A disk-shaped annular shell forming a chamber H for the products of combustion, the central opening b in which tapers upwardly, surmounts the shells D and F and is flanged about its upper edge, as shown at c, to extend it to the inner wall of the casing A, about which it is supported 55 at the flange on a ledge d. On the chamber H is supported in elevated position over its central opening a disk-shaped baffle-plate e, which laps at its edge an annular baffle-plate f, extending about the inner wall of the casing A, near the base of the top C. In the central air-heating furnace-chamber I, formed by the shell F, rises the combustion-chamber K, of general cone shape, having a flue connection g with the chamber H through its inner slanting wall at b. A vertical section of 60 each of the shells D F, extending throughout their entire length, is cut out, and the chamber G is closed at its opposite ends, thus formed by vertical walls i i', Figs. 4 and 5, 65 between which extends near the base of the furnace and through an opening in the outer casing A a door-closed chamber L, leading 70 into the base portion of the conical chamber K. A diaphragm M extends spirally within 75 the chamber I from near its upper end at the wall i', across the space between the walls i i', downward about the exterior of the chamber K and terminates with its lower end at the back of the chamber I, and underneath 80 the outer end of the spiral diaphragm the space in the chamber I between the wall i' and conical chamber K is closed by a vertical partition k. The space between the shells 85 A and D is closed at the side of the fire-box 90 L, adjacent to the wall i, by a vertical partition k', extending from the base of the furnace to the upper ends of the shells.

While the nature of the fuel for use with my improved furnace structure is immaterial, 95 I show a burner N in the base of the chamber K suitable for burning gas, with a supply-pipe l leading thereto in the box L. The hot products of combustion generated in the conical chamber K discharge from its upper narrower end through the flue g into the chamber H, at one side of a partition m therein, shown extending across it in general Z shape, and they course around that chamber, in-

tensely heating its walls, to the outlet *o* there-in at the opposite side of the partition. From the outlet *o* the hot gases enter the chamber *G* through a duct *o'*, Fig. 7, shown depending 5 in the air-chamber *E*, and circulate in the chamber *G* to the discharge-pipe *h* at the side of the furnace opposite that at which the opening *o* is provided, and the discharge-pipe conducts the spent gases to any desired point 10 of escape. The supply of fresh air to be heated enters the chamber *E* near its base, at an opening therein adjacent to the partition *k'* and covered by a sliding door *O*. The air fills that chamber and circulates about it in 15 contact with the shell *D*, from which it takes up heat transmitted to the shell by the partly-spent gases coursing in the contrary direction through the chamber *G*. When the air thus initially heated by the gases in the pre- 20 liminary-heating chamber *G* reaches that part of the chamber *E* adjacent to the end wall *i'* of the chamber *G*, it passes between the vertical partitions *k* and *k'* into the inner air-chamber *I*, underneath the spiral diaphragm 25 *M*, and about the intensely-hot conical chamber *K* till it passes the lower inner end of the diaphragm, whence it rises in a very hot condition in the chamber *I* above the spiral dia- 30 phragm into contact with the intensely-hot disk-shaped chamber *H* and through the central opening *b* therein into the dome or top *C*, being more or less retarded in its rise to hold it the longer under subjection to heat in the chamber *I* and the better to distribute 35 it in the dome to the pipes at *a* by the baffles *e f*. The combustion-chamber should be fed with heated rather than cold air. Accord- 40 ingly I provide a duct *p* for introducing air from the chamber *I* to the chamber *L*. The shape of the combustion-chamber *K*, whereby it is restricted toward its upper end, is 45 peculiarly advantageous in promoting combustion of the gases, whereby they are hottest therein and in the chamber *H*, thereby ren- 50 dering most intensely hot the surfaces with which the air comes into contact toward the end of its course to the dome *C* after being preparatorily warmed by the products of combustion after they have parted with the 55 greater portion of their heat. Moreover, the hot air supplied to the dome *C* is caused by my improved construction to enter it at its center from below, with the advantage of a tendency to induce uniform distribution of the hot air to the pipes at *a*.

What I claim as new, and desire to secure by Letters Patent, is—

1. In a hot-air furnace, the combination of an outer casing, shells therein forming a pre- 60 liminary-heating chamber and an inner air-chamber and forming with said casing an outer air-chamber through which and said preliminary-heating chamber course, respec- 65 tively, the air to be heated and the products of combustion for heating it, said inner air-chamber communicating with said outer air- 70 chamber through an opening in said prelimi- 75 nary-heating chamber, a shell in said inner air-chamber forming a combustion-chamber, an annular shell forming a heating-chamber 70 surmounting said chambers and communicat- 80 ing with said combustion and preliminary- heating chambers, and a dome covering said annular shell and forming a hot-air chamber above it having communication with said in- 85 ner air-chamber only through the opening in said annular shell, substantially as described.

2. In a hot-air furnace, the combination of an outer casing, shells therein forming a pre- 80 liminary-heating chamber and an inner air- 85 chamber and forming with said casing an outer air-chamber through which and said preliminary-heating chamber course, respec- 90 tively, the air to be heated and the products of combustion for heating it, said inner air- 95 chamber communicating with said outer air- chamber through an opening in said prelimi- 100 nary-heating chamber, a shell in said inner air-chamber forming a combustion-chamber, an annular shell forming a heating-chamber 100 surmounting said chambers and containing a transverse partition from opposite sides of which it communicates, respectively, with said combustion-chamber and said prelimi- 105 nary-heating chamber, and a dome covering 110 said annular shell, substantially as described.

3. In a hot-air furnace, the combination of an outer casing, shells therein forming a pre- 100 liminary-heating chamber and an inner air- 105 chamber and forming with said casing an outer air-chamber through which and said preliminary-heating chamber course, respec- 110 tively, the air to be heated and the products of combustion for heating it, said inner air- 115 chamber communicating with said outer air- chamber through an opening in said prelimi- 120 nary-heating chamber, a shell in said inner air-chamber forming a combustion-chamber, a diaphragm disposed about said combustion- 125 chamber in said inner air-chamber and ex- 130 tending from one side of said opening, an annular shell forming a heating-chamber sur- 135 mounting said chambers and communicating with said combustion and preliminary-heating chambers, and a dome covering said an- 140 nular shell, substantially as described.

4. In a hot-air furnace, the combination of an outer casing, shells therein forming a pre- 120 liminary-heating chamber and an inner air- 125 chamber and forming with said casing an outer air-chamber through which and said preliminary-heating chamber course, respec- 130 tively, the air to be heated and the products of combustion for heating it, said inner air- 135 chamber communicating with said outer air- chamber through an opening in said prelimi- 140 nary-heating chamber, a conical shell in said inner air-chamber forming a combustion- 145 chamber, a diaphragm spirally disposed about said combustion-chamber in said inner air- 150 chamber and extending from one side of said opening, an annular shell forming a heating- 155 chamber surmounting said chambers and com- 160 municating with said combustion-chamber at

its smaller end and with said preliminary-heating chamber, and a dome covering said annular shell, substantially as described.

5. In a hot-air furnace, the combination of an outer casing, shells therein forming a preliminary-heating chamber and an inner air-chamber and forming with said casing an outer air-chamber through which and said preliminary-heating chamber course, respectively, the air to be heated and the products of combustion for heating it in relatively-contrary directions, said heating-chamber having an opening extending through it and being closed by end walls at said opening, through which said inner and outer air-chambers communicate, a partition extending at one side of said opening across said outer air-chamber, a shell in said inner air-chamber forming a combustion-chamber, a partition extending from the opposite side of said opening to said combustion-chamber, a diaphragm extending from said opening about the shell in said inner air-chamber, an annular shell forming a heating-chamber surmounting said chambers and communicating with said combustion and

preliminary-heating chambers, and a dome covering said annular shell, substantially as described.

6. In a hot-air furnace, the combination of an outer casing, shells therein forming a preliminary-heating chamber and an inner air-chamber and forming with said casing an outer air-chamber through which and said preliminary-heating chamber course, respectively, the air to be heated and the products of combustion for heating it, said heating-chamber having an opening extending through it connecting said inner and outer air-chambers to cause the air to be heated to course through them successively, a dome covering said chambers, and an annular shell forming a heating-chamber surmounting said chambers, with its opening over the inner air-chamber, said annular chamber discharging into said preliminary-heating chamber, substantially as described. 30 35 40 45

GEORGE THOMSON.
